UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

CAM MECHANISM FOR KNITTING MACHINES.

Application filed October 1, 1920. Serial No. 414,085.

To all whom it may concern:

Be it known that I, GEORGE P. BOSWORTH, a citizen of the United States, and a resident of Central Falls, in the county of Providence and State of Rhode Island, have invented an Improvement in Cam Mechanism for Knitting Machines, of which the following description, in connection with the accompanying drawings, is a specification, like characters on the drawings representing like parts.

This invention relates to knitting mechanisms and particularly to instruments for operating web holders, sinkers or similar elements and is an improvement over the invention disclosed in my copending application Serial No. 334,477 filed October 30, 1919, Patent 1,416,257 of May 16, 1922.

The invention will best be understood by reference to the following description taken in connection with the accompanying drawings wherein are illustrated certain embodiments thereof.

In the drawings:

Fig. 1 is a detail plan view, partly in section, of a so-called sinker ring upon which the various cams for operating the sinkers or web holders are supported.

Fig. 2 is a section taken on the curved line 2-2 of Fig. 1;

Fig. 3 is a vertical section taken approximately on the line 3-3 of Fig. 1 showing the cap ring and the bed ring upon which said cap ring is mounted, a portion of the needle cylinder and needle and web holder mounted in their respective members.

The present invention is applicable to various types of machines but the present embodiment involves a circular knitting machine having the principal characteristics of the so-called Banner machine disclosed in the Hemphill Patent No. 933,443 patented September 7, 1909.

Furthermore the invention is capable of use with both spring beard and latch needle machines. In the type of knitting machine disclosed the needle carrier is of cylindrical form and contains a circular series of independently movable needles, the needle cylinder and cam ring having relative rotary movement so as to effect the operation of the reciprocating elements, herein web holders or sinkers.

In the drawings, 1 represents a needle cylinder having a series of needles 2 arranged

to be reciprocated therein in the usual manner. Attached to the cylinder 1 is a sinker or web holder bed ring 3 having the usual grooves 4 radially disposed with relation to the center of the needle cylinder to receive the web holders or sinkers 5.

The needles 2 are raised and lowered in the usual loop forming manner by appropriate knitting cams, not here shown.

In some machines the reciprocating elements, above referred to, are employed to sink the yarn between the stems or fingers of the needles when in their elevated positions while, in other machines, similar elements may be used for holding the web during the raising of the needles to prevent said web from being elevated therewith particularly where no tension is applied to the knitted fabric.

When such elements are used means are required to impart the necessary reciprocating movements thereto in order to effect the cooperation of said elements with the needles and, whether sinkers or web holders are employed, similar reciprocating means are necessary.

In the present example the reciprocating elements are in the form of web holders, herein indicated by numerals 5 and these web holders are of any suitable design for engaging the work and holding the same during the raising of the needles to prevent said work from being carried upwardly thereby. These web holders, as is customary with such elements, are provided with operating butts 6 herein projecting upwardly from the upper edge of the web holders.

To reciprocate said web holders, the present embodiment involves the use of a cap ring 7 comprising an outer member 8 and an inner member 9, the latter being arranged concentric with said outer member and engaging said outer member along the annular line 10. The outer member 8 has an annular portion 11 while the inner member 9 has an annular portion 12 separated from the annular portion 11 by an annular groove 13 within which the operating butts 6 of the web holders are arranged to project so that said butts may engage and be controlled by the opposed faces of the members 11 and 12.

The under faces of said annular members lie substantially in the same plane, as shown at 15, Fig. 2, and are adapted to en-

gage the upper edges of the web holders and rest upon the corresponding upper face of the web holder bed ring 3 that is, upon the tops of the walls of the grooves for the web holder, thus providing suitable support and guiding means for said ring. The outer margin of the ring 7 is extended at 14 below the upper edge of the web holder bed ring 3 and constitutes a guide for said cap ring, thus properly positioning the latter upon said bed ring.

In knitting machines with which the present mechanism is to be used, the needle carrier and the cams which reciprocate the needles in the grooves of the cylinder, are capable of relative rotary and reciprocatory movements and the mechanism for effecting these relative movements are very well known to those skilled in the art, therefore no description or illustration thereof is believed necessary.

During the reciprocating movements of the knitting machine it is desirable to effect a relative movement between the cam ring and the reciprocating elements or web holders 5 and in the present example means are provided consisting of a two-armed bracket 16 attached to said cap ring herein by screws 17.

30 The arms 18 of said bracket extend in substantially radial directions from said ring and support, adjacent their outer ends, adjustable stop screws 19. The screws 19 are arranged so as automatically to engage 35 a standard 20 carried by some part of the knitting machine frame and herein said standard constitutes the support for the latch ring or yarn guide supporting member and is carried by a part which does not move with the needle cylinder thereby creating a relative movement between said cap ring and said needle cylinder.

The positions of the screws 19 may be such as to permit a slight shogging movement of the ring to take place during the reciprocations of the needle cylinder in a manner common to machines of the type disclosed.

When relative reciprocating movements are desired between the needle cylinder and the cap ring, as in the formation of flat webs, or heel and toe pockets, two sets of cams are usually employed for operating the web holders at the proper intervals to cooperate with the needles in the loop forming operations. Hence in the present example two such sets of cams are provided, each set including a web holder advancing cam and a web holder retracting cam, said sets being suitably spaced to effect the movements of the web holders at the proper points in the knitting.

In the present example the retracting cam members are shown at 21 and 22 mounted upon the inner ring member 9 while the

advancing cam members, as shown at 23 and 24, are carried by the outer member 8 of said cap ring and, during the operations of the machine, said inner and outer ring members are caused to cooperate in their action 70 by appropriate stops consisting of brackets 25 secured to one of the ring members, herein the outer member 8 and bearing adjusting screws 26 arranged in opposed relation to engage opposite portions of an abutment 27 secured to the other ring member, herein the member 9. Obviously the brackets 25 may be disposed at predetermined distances apart so as to cause the screws 26 to engage said abutment when desired but herein in said brackets are placed so close together that but very slight relative movement is permitted to take place between said ring members.

The retracting cam members 21 and 22 85 may embody various forms but herein said members are made in sections conforming substantially to the dimensions of the annular portion of the inner ring member 9, and these cam members are halved at 28 and 29 as shown in Fig. 2 and are pivoted together and to said inner ring member 9 by a common pivotal stud 30, and within a gap or recess formed in the annular portion of said ring 9 so that said members will set 90 flush with the lower plane 15. The combined vertical thickness or depth of said halved portions are equal to the depth of the annular groove 13.

Short sections of said members 21 and 22 100 adjacent their free ends, are offset at 31 and 32 and these sections engage the butts of the web holders and cause them to be retracted beyond the circular path normally followed when said web holders are in engagement 105 with the outer edge of the annular portion 12 representing the advanced positions of said web holders.

The inner edges of the members 21 and 22 110 are cut away at 33 and 34 respectively so that the total lateral extent of the cam members at the offset portions will be the same as the remaining portions of said cams and also the annular member 12. By reason of the arrangement of said members 21 and 22, the positions of the web holder deflecting portions 31 and 32 may be varied relatively to the axis of the ring to effect the desired throw of the web holders, and to secure said members 31 and 32 in the desired 115 positions, means are herein provided consisting of screws 35 and 36 extending through slots 37 in the upper part of said ring and into screw-threaded engagement with said cams so that, by turning said screws to clamp the free ends of the cams against the under face of the ring, said cams 120 will be maintained in the desired operative positions.

The free ends of the retracting cam mem- 125

bers 21 and 22 are curved at 38 on an arc, the axis whereof is coincident with the axis of the screw 30 and these curved ends are adapted to engage correspondingly curved surfaces 39 at opposite ends of the annular member 12 which, in order to prevent wear, due to the constant hammering of the web holders, are composed of hardened steel sections 40 inserted in appropriate recesses formed at the end of said member 12 so as to lie flush with said member 12 and form continuations thereof.

The advancing cam members 23 and 24 for the web holders are provided with cam faces 41 arranged in suitable spaced relation to cooperate with the cams 31 and 32, and these cam surfaces are formed upon suitable inserts 42 and 43 set into a suitable recess or gap 44 formed in the outer annular member 11. The ends of the members 42 and 43 bearing the cam surfaces 41 are adjustably mounted with respect to the cams 31 and 32 to effect variations in the movements of said web holders, hereby by slotting the upper portion of the ring member 8 at 45 and extending through said slots are screws 46 which have screw-threaded engagement with the ends of said cam members and are adapted to secure the same firmly against the under face of the outer member 8. The opposite ends of said members 42 and 43 are pivoted at 47.

While I have herein shown and described one embodiment of my invention and have disclosed and discussed in detail the construction and arrangement incidental to such disclosure, it is distinctly to be understood that the invention is limited neither to the mere details or relative arrangement of parts nor to the specific application herein shown but that extensive variations may be made without departing from the principles thereof.

Claims.

1. In a knitting machine adapted for rotary and reciprocating knitting, a series of readily movable web holders or the like, a ring having inner and outer members capable of relative circumferential or shogging movement and adapted to engage opposed portions of said web holders, the outer member of said ring carrying two spaced web holder advancing cams and the inner member of said ring carrying a pair of retracting cams, mounted for relative adjustment one to the other and adapted to cooperate with said advancing cams respectively.

2. In a knitting machine adapted for rotary and reciprocating knitting, a series of readily movable web holders or the like, a ring having inner and outer members capable of relative circumferential or shogging movement and adapted to engage opposed portions of said web holders, the

outer member of said ring carrying two spaced web-holder advancing cams and the inner member of said ring carrying a pair of retracting cams, said retracting cams comprising two parts having a common pivot and adapted to be swung independently thereon for adjustment and cooperation with respect to said advancing cams.

3. In a knitting machine adapted for rotary and reciprocating knitting, a series of readily movable web holders or the like, a ring having inner and outer members capable of relative circumferential or shogging movement and adapted to engage opposed portions of said web holders, the outer member of said ring carrying two spaced web-holder advancing cams and the inner member of said ring carrying a pair of retracting cams, said retracting cams having a common pivot carried by said inner member and individually adjustable thereabout into cooperating relation with the respective advancing cams.

4. In a knitting machine adapted for rotary and reciprocating knitting, a series of readily movable web holders or the like, a ring having inner and outer members capable of relative circumferential or shogging movement and adapted to engage opposing portions of said web holders, the outer member of said ring carrying two widely spaced web-holder advancing cams, and the inner member of said ring having a curved portion 12, the ends whereof are spaced apart substantially the distance of said advancing cams from each other, said inner member of the ring also carrying a pair of retracting cams mounted for relative adjustment one to the other and extending in opposite directions substantially to the ends of said portion 12, so as to cooperate therewith.

5. In a knitting machine adapted for rotary and reciprocating knitting, a series of readily movable web holders or the like, a ring having inner and outer members capable of relative circumferential or shogging movement and adapted to engage opposing portions of said web holders, the outer member of said ring carrying two widely spaced web-holder advancing cams, and the inner member of said ring having a curved portion 12, the ends whereof are spaced apart substantially the distance of said advancing cams from each other, said inner member of the ring also carrying a pair of retracting cams themselves comprising two parts having a common pivot and adapted to be swung independently thereon for adjustment and cooperation with respect to said advancing cams, said retracting cams extending substantially into contact with the ends of the portion 12.

6. In a knitting machine adapted for rotary and reciprocating knitting, a series of

readily movable web holders or the like, a ring having inner and outer members capable of relative circumferential or shogging movement and adapted to engage opposing portions of said web holders, one of said members carrying an abutment, and the other of said members carrying adjustable stops to engage therewith and limit the extent of the relative circumferential or shogging movement, the outer member of said ring carrying two spaced web-holder advancing cams, and the inner member of said ring carrying a pair of retracting cams mounted for relative adjustment one to the other and adapted to cooperate with said advancing cams respectively.

7. In a knitting machine adapted for rotary and reciprocating knitting, a series of readily movable web holders or the like, a ring having inner and outer members ca-

pable of relative circumferential or shogging movement and adapted to engage opposing portions of said web holders, one of said members carrying an abutment and the other of said members carrying at opposite sides of said abutment a pair of brackets having adjustable stops extending into substantially close proximity to opposite faces of said abutment, thereby to limit the relative circumferential or shogging movement, the outer member of said ring carrying two spaced web-holder advancing cams and the inner member of said ring carrying a pair of retracting cams mounted for relative adjustment one to the other and adapted to cooperate with said advancing cams respectively.

In testimony whereof, I have signed my name to this specification.

GEORGE P. BOSWORTH.
